DRUM OR CONTAINER FOR OIL OR OTHER LIQUIDS

Thomas Dorsey Owings, Flushing, N. Y.

Application February 26, 1931. Serial No. 518,421

7 Claims. (Cl. 220—86)

In the business of selling oil it is a common practice for the oil distributor to deliver his oil in drums or cans which are the property of the distributor and which are returned to the distributor after the oil has been sold to be refilled and used again. One difficulty which the distributors have encountered has been due to the fact that dealers or managers of oil stations, if they are dishonest, will refill a drum or can with inferior and cheaper oil and sell it as the product of the original distributor.

The object of the present invention is to furnish an oil can or container which is so constructed that it will be practically impossible for the dealer or seller to refill the can in this way.

My invention consists in providing the oil drum or container with a feed pipe through which the drum is to be filled or emptied and which is furnished with a check valve opening outwardly to permit the discharge of oil from the drum but closing to prevent the drum from being refilled. The valve member of the check valve is provided with a removable cap which can be unscrewed from the valve member by inserting a suitable key in and through the feed pipe constructed to engage with the movable cap and enable the cap to be unscrewed from the check valve. When the cap is thus unscrewed it can be removed from the feed pipe and the check valve will be left with an open passage through which the drum can be refilled with a fresh supply of oil. The removable cap and key are so constructed that the cap cannot be unscrewed and removed except by some one having a special form of key constructed to match and engage with the removable cap.

In the drawing Fig. 1 shows a sectional view of an oil drum embodying my invention.

In Fig. 2 is shown a sectional view of the feed pipe showing the upper end closed with a screw plug which is inserted when the can is full and ready for delivery by the distributor and showing the lower end of the pipe with the check valve mounted therein.

Fig. 3 is a sectional view at the lower end of the feed pipe showing the socket of the key in engagement with the removable cap of the check valve.

Fig. 4 is a sectional view of the structure shown in Fig. 3 on the line 4—4 looking downward.

Fig. 5 is a bottom end view of the key.

Fig. 6 is a sectional view of the lower end of the key showing the pin on the top of the re-

movable cap in engagement with the recess and with the lower end of the key.

Fig. 7 is an elevation view of the key. Referring to the drawing, 1 is an ordinary oil drum or container. This container is provided with a feed tube 2 which is attached at its upper end in any suitable way to the top of the oil drum. The feed tube extends downwardly in the drum, preferably to a point near the bottom thereof and is provided at its lower end with a check valve 3 which opens outwardly so as to permit the oil to flow out of the drum through the feed pipe and which closes when the oil flows in the other direction so as to prevent the drum from being refilled. As is shown in the drawing the check valve is placed a considerable distance from the outer end of the feed pipe. 4 is a pump of any construction by means of which the oil can be discharged from the drum. This pump is shown diagrammatically in Fig. 1. The construction of this pump is no part of the invention. It is adapted to be screwed into the upper part of the feed pipe.

The construction of the check valve is shown in Figs. 2 and 3. 5 is the fixed plate of the valve which is secured to the lower end of the feed tube in any suitable way as by welding, such as is illustrated at 6. 7 is the valve proper which is hinged at 8 to the plate 5 so that the valve will swing upwardly and permit the oil to flow out of the drum. The valve proper is provided with a central aperture 9 which is screw threaded as shown. 10 is a removable cap provided with a projection, at the lower end which is screw threaded as shown, the screw thread of this projection being adapted to engage with the screw thread in the opening of the valve proper. 11 is a groove in the upper part of the removable cap by means of which the key can be connected with the cap as hereinafter explained. The head of the removable cap is made hexagonal or in any other shape to enable it to engage with the lower end of the key and be turned thereby. 12 is a gasket of rubber or suitable material fitted into a recess in the plate 5 to form a seat for the valve proper 7. 13 is a key for removing the cap of the check valve. This key consists of a stem 14 having a handle 15 at the top and a socket piece 16 at the bottom provided with a recess adapted to fit over the top of the removable cap on the check valve. The socket piece 16 has a recess shaped to fit the top of the removable cap. This socket piece is provided with three projections 17 adapted to guide the key when it is inserted in the feed tube 2. One of these pro-

sections 17 is provided with a central hole as shown in Fig. 3 in which a pin 18 is arranged to be moved back and forth so that the inner end of the pin may engage with the groove 11 in the cap. The pin is pressed inwardly by a coil spring 20 placed in the hole in the projection 17 which spring can be adjusted by the nut 21 which is adapted to be screwed into the outer end of the hole or aperture in the projection 17. The stem 14 of the key is made hollow so that it has a central passage as shown in Fig. 3 to receive the pin 22 which is adapted to be moved up and down in the key for purposes hereinafter explained. The upper end of the pin 22 is provided with a handle 23. The upper end of the feed tube 2 is provided with a vent 24 to permit the inflow of air when the oil is being removed from the drum. This is shown in Fig. 2 and is arranged so that it will be left open when the pump 4 is inserted but will be closed when the drum has been filled and is closed by the cover 25 which is adapted to be screwed into the upper end of the feed tube 2 after the drum has been filled and is ready for shipment.

25 The operation of my invention is as follows: A drum filled with oil is sold to a dealer or supply station. The dealer or manager of the supply station unscrews the cover 25 and inserts any suitable form of oil pump 4. When a sale of oil is made the oil is pumped out of the drum in such quantity as may be desired, the check valve 3 opening upwardly for that purpose. When the drum has been emptied, all but some remaining oil in the tube 2, the pump is unscrewed, the remaining oil is allowed to run out and the drum is returned to the distributor to be refilled.

40 The distributor inserts the key in the tube 2, the lower end of the key is guided in the tube by the projections 17, and by being turned part of a revolution will cause the socket at its lower end to engage with the projection on the upper part of the removable cap of the check valve. When the key is pressed down on the check valve, the pin 18, the inner edge of which is rounded, will slip over the top of the cap and into the groove 11. The key is then turned so as to unscrew the cap from the check valve. The key is then removed from the drum bringing with it the removable cap and the valve proper is left with an opening through its center through which the drum can be filled with a fresh supply of the genuine or proper grade of oil. After the can has been filled the key holding the cap at its lower end is re-inserted in the tube 2 and the removable cap is screwed into the valve proper of the check valve. The key is then removed. In order to prevent the lifting of the valve proper and the possible friction or jamming of the parts when this is done, the rod 22 is pressed 60 downwardly in the key so as to bear on the top of the cap while the stem of the key is being raised. In this way the pin 18 will be caused to slip past the edge of the groove in the cap and the tendency of the valve proper to rise will be prevented. When the pin has slipped out of the groove and over the top of the cap the key can be removed without difficulty. The cover 25 is then screwed in place and the can of oil is ready for sale and delivery.

70 To prevent unauthorized people from removing the removable cap of the check valve by using a similar key, the key and cap are provided with suitable registering devices as a result of which no key will work unless it is especially constructed for the particular form of check valve employed. Such

80 a device is shown in Figs. 5 and 6, Fig. 5 being a bottom end view of the key 13 and Fig. 6 being a sectional view of the lower end of the key. In this particular form or modification the upper end of the cap is provided with a pin 27 which is adapted to register with and enter a hole or recess 26 in the socket member of the key. In this construction when the key is inserted to move the cap it must be turned in the tube 2 until the pin 27 enters the recess 26.

85 In this application I have shown and described a form of check valve which I believe to be new, namely, one having a valve member provided with a removable cap for opening or closing a passage through the valve member. I do not claim here- 90 in this improvement in check valves but I reserve the right to claim the same in a separate application.

95 My invention is especially applicable to drums or containers used for selling oil but it is obvious that these drums or containers may be used for any liquid.

What I claim as new and desire to secure by Letters Patent is:

1. The combination with a drum of a feed pipe 100 supported therein, a check valve in the feed pipe opening outwardly, a screw-threaded opening in the valve proper of the check valve, a removable cap screw threaded at its lower end and adapted to be screwed into the opening in the valve proper, 105 a projection on the top of the removable cap provided with a groove, a key having a socket at its lower end adapted to fit over the projection on the cap, a spring pressed pin carried by the socket and adapted to project into the groove of the cap and 110 to lock the key to the cap, whereby the removable cap may be unscrewed and removed from the valve.

2. The combination with a drum of a feed pipe 115 suitably supported therein, a check valve in the feed pipe opening outwardly, the valve proper of the check valve having a screw-threaded opening therein, a removable cap adapted to be screwed into the said opening so as to close the same, a key adapted to be inserted in the feed pipe and 120 to engage with the removable cap whereby the removable cap may be unscrewed by the key and removed from the valve, leaving an opening there- 125 through, and registering devices consisting of a pin and a hole to receive the pin, one of the cap and the other on the key, so that the cap can be removed only by a key made to fit it.

3. The combination with a drum of a feed pipe 130 supported therein, a check valve in the feed pipe opening outwardly, a screw-threaded opening in the valve proper of the check valve, a removable cap screw threaded at its lower end and adapted to be screwed into the opening in the valve proper, 135 a projection on the top of the removable cap provided with a groove, a key having a socket at its lower end adapted to fit over the projection on the cap, a spring pressed pin carried by the socket and adapted to project into the groove of the cap and 140 to lock the key to the cap, the key being provided with a passage, and a pin adapted to be moved in said passage and to bear on the removable cap, whereby the removable cap may be unscrewed and removed from the valve.

4. The combination with a drum or container 145 of a feed pipe suitably supported inside the drum, a check valve at the lower end of the feed pipe opening outwardly, provided with a removable cap, and a key adapted to be inserted in the feed pipe and to engage with the removable cap, 150

whereby the cap may be removed and the drum may be refilled.

5. The combination with a drum or container of a feed pipe suitably supported inside the drum, a check valve in the feed pipe opening outwardly and placed a considerable distance from the outer end of the feed pipe and provided with a removable cap and a key adapted to be inserted in the feed pipe and to engage with the removable cap whereby the cap may be removed and the drum refilled through the feed pipe.

6. The combination with a drum or container of a feed pipe suitably supported inside the drum, a check valve in the feed pipe opening outwardly and placed a considerable distance from the outer end of the feed pipe, the valve proper of the check valve having a screw-threaded opening therein, a removable cap adapted to be screwed into the said opening so as to close the same, a key adapted

20 to be inserted in the feed pipe and to engage with

the removable cap whereby the removable cap may be unscrewed by the key and removed from the valve leaving an opening therein through which the drum may be refilled.

7. The combination with a drum or container of a feed pipe suitably supported therein, a check valve in the feed pipe opening outwardly and placed a considerable distance from the outer end of the feed pipe, the valve proper of the check valve having a screw-threaded opening therein, a removable cap adapted to be screwed into the said opening so as to close the same, a key adapted to be inserted in the feed pipe and to engage with the removable cap whereby the removable cap may be unscrewed by the key and removed from the valve leaving an opening therethrough, and registering devices, one on the cap and the other on the key, so that the cap can be removed only by a key made to fit it.
